(57) **CLAIM**

The ornamental design for a bottle dispenser, as shown and described.

DESCRIPTION

In a preferred embodiment, the nature of this product is as a bottle dispenser in the form of a cap structure.

FIG. 1 is a left, front, upper perspective view of a bottle dispenser embodying our new design;

FIG. 2 is a right, rear, upper perspective view thereof;

FIG. 3 is a top plan view thereof;

FIG. 4 is a bottom plan view thereof;

FIG. 5 is a left side elevational view thereof, the right side elevational view being a mirror image thereof;

FIG. 6 is a rear elevational view thereof; and,

FIG. 7 is a front elevational view thereof.

The broken line showing of ridges in FIGS. 1-7 and of mounting structure in FIG. 4 are for illustrative purposes only and form no part of the claimed design.
